UNITED STATES PATENT OFFICE.

FRANK EISEL, FRANK HAGEN, AND ARTHUR SCHROEDER, OF BREESE, ILLINOIS.

RAILWAY-TIE.

1,017,042.

Specification of Letters Patent. Patented Feb. 13, 1912.

Application filed March 30, 1911. Serial No. 617,846.

To all whom it may concern:

Be it known that we, FRANK EISEL, FRANK HAGEN, and ARTHUR SCHROEDER, citizens of the United States, residing at 5 Breese, in the county of Clinton and State of Illinois, have invented certain new and useful Improvements in Railway-Ties, of which the following is a specification.

This invention relates to railway ties, and 10 it relates particularly to that class of these articles wherein the bodies of the ties are composed of concrete.

The object which we have in view is to provide a railway tie of the kind referred 15 to which shall be strong and durable, and which shall be so formed, and provided with such attachments that the rigid securing of railway rails to the ties shall be capable of being effected by cheap and easily 20 operated means.

With these objects in view the invention consists of a tie having the generic and specific features of construction and arrangement of the parts substantially as herein- 25 after described and claimed.

The invention is illustrated in the accompanying drawing in which;

Figure 1 is a perspective view of a railway tie made in accordance with our invention, showing by dotted lines a portion of a railway rail secured to the tie; Fig. 2 is a longitudinal vertical sectional view of a tie and the means for securing a rail thereto; and, Fig. 3 is a perspective view of 35 the means for attaching a rail to the tie, the same being shown removed from the tie.

In this drawing 1 represents the body of a tie which is composed of concrete and is approximately of the size of the wooden ties in common use. The body 1 of the tie is reinforced by metal rods 2 extending longitudinally through the body of the tie, one of the rods being preferably located adjacent to each of the four corners of the tie. 40 In order to give strength and rigidity to the body we embed therein and incorporate with it at the time of forming the same a bar 3 of metal which extends from end to end of the tie and which is preferably en- 45 tirely surrounded by the concrete. The bar 50 3 is located at any desired point within the tie, being preferably situated at about the middle thereof.

In order that rails may be attached to the ties, formed as described by means capable 55 of rapid manipulation, and which when secured in place shall insure the rails against displacement, we form near each end of the ties a socket 4 all the sides of which are formed by the material of the tie, and in 60 this socket are placed clamps, consisting of a bed plate 5 of a size to fit closely in the socket and having at one end an overhanging arm 6 adapted to bear upon the face of the flange of a rail at one side thereof. The 65 bed plate 5 has extending transversely thereof a projection 7 which enters a transverse groove 8 in the lower face of an arm 9, which arm has at one end an upward projecting clamp 10 the lower face of which 70 is adapted to bear upon the flange of a rail. The arm 9, the plate 5, the bar 3, and the body of the tie are all provided with openings which are in line with each other when the parts are assembled and through these 75 openings extends a bolt 11, the head of which is preferably located in a countersink in the bottom face of the tie and which receives at its upper end a nut which bears upon the arm 9. The bed plate 5 fitting 80 snugly into the socket in the top of the tie is firmly seated and when a rail placed in position to have the flange project between the arms 6 and the bed plate 5 on one side, and to be retained by the arm 9 on the opposite side it will be firmly held in place by the single bolt 11 thus providing in a simple cheap way for the reliable retaining of the rail in place. Great rigidity and strength are given the construction by passing the 85 bolt 11 through the clamp 10, the bed plate 5, the body of the tie and the plate 3, and should the concrete body become cracked or broken support and maintenance of the rail in place will be insured by reason of 90 the construction and arrangement of the other parts of the device.

Having thus described our invention,

what we claim as new, and desire to secure by Letters Patent, is:—

A railway tie comprising a body of concrete having sockets formed in its upper face, bed plates fitted snugly in the sockets, the bed plate being provided at one end with an overhanging arm and at the other end on its upper face with a transverse projection, a separate clamping arm having a transverse groove in its lower face, a plate embedded in the concrete, and a binding

bolt passing from the lower face of the tie through the embedded plate, the bed plate and the clamping arm.

In testimony whereof we affix our signatures in presence of two witnesses.

FRANK EISEL.

FRANK HAGEN.

ARTHUR SCHROEDER.
